UNITED STATES PATENT OFFICE.

HARRY D. LATHROP AND WALTER H. PAULSON, OF CHICAGO, ILLINOIS; SAID PAULSON
ASSIGNOR TO SAID LATHROP.

COVER-APPLYING MECHANISM FOR CAN-WASHING MACHINES.

1,262,679.

Specification of Letters Patent. Patented Apr. 16, 1918.

Application filed June 9, 1917. Serial No. 173,897.

To all whom it may concern:

Be it known that we, HARRY D. LATHROP and WALTER H. PAULSON, citizens of the United States, and residents of the city of Chicago, county of Cook, and State of Illinois, have invented certain new and useful Improvements in Cover-Applying Mechanism for Can-Washing Machines, of which the following is a specification.

Our invention relates to improvements in milk can washing machines, and has for its object the production of improved means for automatically applying covers to the milk cans after washing and drying of the latter, and before the cans have been discharged from the machine. Heretofore, we have provided means for applying covers to milk cans before discharge of the same from the washing machine, but we have found that frequently covers, as applied by the means heretofore provided by us, were not applied securely enough to the cans and frequently became detached or would readily drop off when the cans were handled. It is the object of the present invention, therefore, to provide improved means for securely applying the covers to the cans so that, when the latter are discharged from the machine, the covers of the same will be fully and securely applied and the danger of the covers becoming readily detached from the cans, as above pointed out, obviated. Other objects will appear hereinafter.

The invention consists in the combinations and arrangements of parts hereinafter described and claimed.

The invention will be best understood by reference to the accompanying drawings forming a part of this specification, and in which,

Figure 1 is a side elevation of the discharge end portion of a can washing machine equipped with cover applying mechanism embodying the invention,

Fig. 2, a section taken on substantially line 2—2 of Fig. 1, and

Fig. 3, a view similar to Fig. 1 illustrating the successive steps in the operation of the cover applying mechanism.

The preferred form of construction as illustrated in the drawings, is shown applied to a milk can washing machine comprising a framework 5 in the lower portion of which is arranged a can guide 6, and in the upper

portion of which is provided a cover guide 7, 55 the cans and covers, lettered A and B, respectively, in the operation of the machine, being adapted to slide along said guides 6 and 7 where the same are subjected to the successive washing, sterilizing and drying treatments. Each can after the cleansing of the same has been completed, is pushed from the guide 6 onto a reversing device 8 which is pivoted at 9, the arrangement being such that the cam which is deposited thereon in 65 inverted position, will, upon rocking of said device 8, be reversed and deposited in upright position onto an inclined discharge guide or chute 10, the can being adapted to slide by gravity down said guide 10. 70

At the same time that a can is pushed from the guide 6, the cover of said can is pushed from the guide 7 onto an inclined guide 7' down which the cover slides by gravity until arrested in its movement by a 75 horizontally disposed shelf 11. The member 11 is pivotally and slidably mounted, the front end thereof being pivotally connected with a leaf 12 secured intermediate its ends to a rockingly mounted shaft 13 which is 80 provided at one end with a crank 13'.

As the can starts sliding down the guide 10, the same is arrested by a horizontally swinging stop arm 14, the movements of said stop arm being controlled by a reciprocating 85 bar 15 carrying, at its front end, a slotted plate 15' which engages with the outer end of the arm 14, the arrangement being such that, when the bar 15 is moved forwardly or to the right as seen in Fig. 1, said arm 90 will be moved to operative position to arrest the can, and, when said bar is moved rearwardly or to the left as seen in said figure, said arm 14 will be swung to releasing position in order to permit of continued movement of the can down guide 10. The exact construction for effecting this arresting of the movement of the can is not important in this application, there being no claim here made thereto. When the arm 14 is thus 100 swung to arresting position as above mentioned, however, the crank 13' of shaft 13 will be engaged by a post 16 arising from the bar 15 which will cause swinging of the members 11 and 12 to effect release of the 105 cover B resting upon the member 11. The cover thus released will pass by gravity down the member 12 and will be directed

or guided by said member 12 and a coöperating member 17 onto position upon the upper end of the can.

The member 17 is in the nature of a paddle fixed to a shaft 18 which is freely rotatable and provided at one end with a crank 18'. Arranged adjacent the member 17 is an actuating lever 19 fulcrumed intermediate its ends as at 20. The lower end of the lever 19 carries a pawl 21 pivoted at 22, said pawl being provided with a stop 23 which is adapted to engage against the adjacent side of said lever to prevent rocking of the lower end of said pawl to the left relative to said lever, as seen in Fig. 1, said pawl being, however, free for swinging in the opposite direction.

Formed upon the plate 15' is an inwardly extending flange or shoulder 24 which is adapted to pass in front of the pawl 21, when said plate and hence the bar 15 are at their forward terminals of movement. The arrangement is such that as said plate and bar are moved rearwardly to swing the arm 14 to releasing position and to permit of continued downward movement of the can upon guide 10, the flange or shoulder 24 will engage with the pawl 21, causing a sudden and violent rocking of the lever 19. The upper end of lever 19 engages with the crank 18' of the shaft 18 and, upon rocking of said lever as mentioned, causes rocking of the paddle 17 upwardly to a position as indicated in full lines in Fig. 3. The arrangement and timing is such that as the can passes down the guide 10, said paddle 17, swinging downwardly by gravity, will strike the cover of the can and force the same down to closed or fully seated position, as seen in dotted lines in Fig. 3. The portion of said paddle which thus contacts with the cover is resilient, the result being that said paddle will be caused to vibrate or bounce upon the cover, delivering a plurality of blows thereon, which positively insures absolute seating of the cover. At the same time this resiliency guards against injury or marring of the cover. With this arrangement, then it will be seen that each can as discharged from the machine will have its cover tightly secured thereto.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having described our invention what we claim as new and desire to secure by Letters Patent is:

65 1. In a machine of the class described, the

combination of a can guide; means for depositing a cover on each can moving along said guide; and means for delivering a blow upon each cover adapted to force the same down into secure engagement with the can 70 onto which the same is deposited, substantially as described.

2. In a machine of the class described, the combination of a can guide; means for depositing a cover on each can moving along 75 said guide; and means arranged over said guide for delivering a blow upon each cover adapted to force the same down into secure engagement with the can onto which the same is deposited, substantially as described. 80

3. In a machine of the class described, the combination of a can guide; means for depositing a cover on each can moving along said guide; and pivotally mounted means for delivering a blow upon each cover 85 adapted to force the same down into secure engagement with the can onto which the same is deposited, substantially as described.

4. In a machine of the class described, the combination of a can guide; means for depositing a cover on each can moving along said guide; and a swingingly mounted paddle arranged over said guide and adapted, subsequently to the deposit of a cover onto a can, to deliver a blow upon the cover 90 adapted to force the same down into secure engagement with the can, substantially as described.

5. In a machine of the class described, the combination of a can guide; means for 100 depositing a cover on each can moving along said guide; and a swingingly mounted resilient paddle arranged over said guide and adapted, subsequently to the deposit of a cover onto a can, to deliver a blow upon the 105 cover adapted to force the same down into secure engagement with the can, substantially as described.

6. In a machine of the class described, the combination of a can guide; means for 110 depositing a cover on each can moving along said guide; a swingingly mounted paddle arranged over said guide and adapted, subsequently to the deposit of a cover onto a can, to strike the cover and force the same down into secure engagement with the can; and means for rocking said paddle to effect 115 actuation of the same at the proper time, substantially as described.

7. In a machine of the class described, the combination of a can guide; means for depositing a cover on each can moving along said guide; a freely swinging paddle arranged over said guide and adapted, subsequently to the deposit of a cover onto a can, 125 to strike the cover and force the same down into secure engagement with the can; and means for rocking said paddle upwardly at the proper interval to effect engagement, at the proper time, of the paddle with the 130

cover; upon the downward swinging of the paddle, substantially as described.

8. In a machine of the class described, the combination of a can guide; means for depositing a cover on each can moving along said guide; vertically movable means arranged over said guide and adapted, subsequently to the depositing of a cover onto a can, to strike the cover and force the same down into secure engagement with the can; and means for moving said cover-striking means to effect actuation of the same at the proper time, substantially as described.

9. In a machine of the class described, the combination of a can guide; means for depositing a cover on each can moving along said guide; a vertically movable member ar-

ranged over said guide and adapted, subsequently to the depositing of a cover onto a can, to strike the cover and force the same down into secure engagement with the can; and means for moving said cover-striking member vertically to effect actuation of the same at the proper time, substantially as described.
